CHUCK.

George Thornhill, Aldridge, England

Application September 29, 1944, Serial No. 556,424
In Great Britain October 12, 1943.

6 Claims. (Cl. 279—7)

This invention relates to chucks for lathes or the like for holding work-pieces which are fixed in position by having screwed engagement therewith. The resistance to the drive is taken through this screwed engagement and consequently the work-piece becomes tightly screwed on the chuck by the pressure of the cutting or other tool thereon and difficulty is experienced in unscrewing the work-piece after the operation thereon and particularly so when a spanner cannot be applied to the work-piece. This invention has for its object a chuck which provides for a quick release of the work-piece.

According to the present invention, the work-piece is screwed against a thrust member on the chuck which is held in position by a movable release member or members or cams which are adapted to be operated to release the pressure on the thrust member and thereby permit the work-piece to be freely unscrewed. The cam or movable release members are conveniently pivotally mounted and a plurality of such members may be simultaneously operated by a common control member.

Referring to the drawings:

Figure 1 is a side elevation of a chuck constructed according to this invention.

Figure 2 is an end view with the work holder and front ring attached to the thrust member removed.

Figure 3 is a sectional side elevation of the body of the chuck.

Figure 4 is a face view of the body of the chuck.

Figure 5 is a plan of a cam.

Figure 6 is a side elevation of the cam.

Figure 7 is a plan view of the trip lever.

Figure 8 is a side elevation of a bridge piece.

Figure 9 is an underside view of the bridge piece, and

Figure 10 is a plan view of the bridge piece with the slide cover plate removed.

According to a convenient embodiment of this invention, the chuck comprises a cylindrical body portion 1 which has a part 2 detachably fixed thereto having an internally screwed stem 1a at the rear end for attachment to the lathe or the like. The front end of the body is adapted to have the work-piece screwed thereon. The means for securing the work-piece varies according to the work-piece. In the construction illustrated the body 1 has a taper bore 3 therethrough and a taper stem having an externally screw threaded head 4 is fixed in the bore and the internally screw threaded work-piece 5 is screwed against the thrust ring 6 slidably mounted on the cylind-

rical outer end of the body 1. The thrust ring 6 has a ring 7 detachably fixed thereto to form an abutment against which the work-piece is screwed. This ring 7 is interchangeable and therefore can be designed according to the size or shape of the screwed head 4. If the work-piece is externally screw threaded, the head 4 is internally screw threaded and when the work-piece is screwed on the head it applies pressure to the thrust member and if the thrust member is moved away from the work-piece the pressure of the work-piece thereon is relieved. The thrust member is held in position by a plurality (in the example, four) of abutment cams 8. These cams comprise pins 9 which are pivotally mounted in radial holes 10 in the body 1 of the chuck and the portion of each pin lying above the cylindrical body has a lever arm 11 thereon which engages a notch 12 in a cam control ring 13 rotatably mounted on the body 1. The upper portion of the pin 9 in front of the arm 11 has a cam face which is V-shaped to form two flat faces and in one position one flat face 14 holds the thrust member in the forward position with the work-piece 5 screwed thereagainst. The control ring can be rotated by a bar inserted in a tommy hole or one cam can be rotated and the control ring transmits movement to the other cams. When the control ring 13 is rotated the lever arms 11 are pivoted over and the other flat face 15 lies opposite the thrust member and this face is set back so that the thrust member 6 is free to move rearwardly and relieve the pressure on the work-piece, whereby such work-piece can be freely unscrewed from the chuck. The thrust member 6 has a limited sliding movement on the body of the chuck by means of a pin 16 screwed through the thrust member and engaged in a slot in the body of the chuck. The thrust member 6 lies over a shoulder 17 on the cam pin and holds the cam in the pivot hole. The control ring 13 is normally spring pressed in a direction to hold the cams in the operative position and for this purpose springs 18 are mounted in an annular groove 20 in the body of the chuck and under the control ring. One end of each spring 18 bears against a pin 21 fixed to the control ring and the other end bears against a pin 22 fixed to the body of the chuck. A stop co-acting with a pin 21 prevents the springs moving the control ring beyond the position when the cams are in the operative position. When therefore the control ring 13 is turned the pressure on the work-piece is immediately released. The springs restraining the control ring, will not have sufficient

pressure to again bind the work-piece. The diameter of the control ring and thrust piece is such that the cams do not project therebeyond.

Provisions may be made to automatically release the chuck whilst it is rotating. In one form, a lever 23 is attached to one of the cams and when such lever strikes against a stop or pawl attached to a stationary part of the machine, the cams will be operated to release the thrust member. A pawl 24 is carried by a pin 25 pivotally mounted on the bridge piece 26 fixed to the machine and the upper end of the pin carries a lever 27. A slide 28 is mounted on the bridge piece and has a bevelled shoulder which is adapted to move against the lever 27 and pivot such lever to withdraw the pawl 24 out of the path of the trip lever 23. The slide is normally pressed outwardly by the spring 29 in position to hold the lever 27 so that the pawl is in the inoperative position (as shown by full lines Figures 9 and 10) but when the slide is moved inwardly it moves free of the lever 27 (as shown by broken lines Figure 10) and allows the pawl to be spring held in the operative position by the spring 30. The spring 29 is located in a slot 32 and bears against the end of the slot and a pin 33 fixed to the bridge piece. The slide is held in position by the cover plate 34 which has a central rib bearing against the inner side of the slide and forming a slide guide. When a tool is operating on the work-piece it tends to be screwed tight against the thrust member and would require an instrument to remove it. The bridge piece 26 is mounted concentric with the chuck so that the lever 23 travels in the groove 26a and the pawl 24 is mounted in the recess 26b at the side of the groove. If, while the chuck is rotating, the slide 28 is pressed inwardly, the trip lever 23 is turned by the pawl 24 and the thrust member is free to move inwardly and relieve the grip on the work-piece. If the work-piece has been subjected to a screw threading operation it has to be unscrewed by reversing the rotation of the chuck and the bridge piece carries a second pawl 24a mounted on a pin and having a lever 27a which is controlled by the slide 28a. If this slide is pressed inwardly, when the rotation of the chuck is put into reverse, the pressure of the work-piece on the thrust member is relieved leaving it free to be unscrewed. The pawls 24 and 24a are reversely arranged so that one is used when the chuck rotates clockwise and the other comes into action when the chuck rotates anti-clockwise. The slides can be held in the pushed-in position by means of a pin 31 which engages in the end of a slot 32 when passed through a hole in the bridge piece. When the chuck is rotated during the screwing operation the lever 23 will ride over the pawl, but when the chuck is reversed the pawl will operate the trip lever and leave the thrust member free to move inwardly.

I claim:

1. A chuck for holding a work-piece having screwed engagement therewith comprising a chuck body, a thrust member slidably mounted on the said body, means on the said body on which the work-piece is fixed by screwed engagement against the thrust member, a plurality of cams pivotally mounted on the body of the chuck and forming movable abutment members against which the thrust member bears and which are adapted to be pivoted away from the thrust member, a cam control ring rotatably

mounted on the chuck body and coupling the cams together so that they rotate in unison.

2. A chuck for holding a work-piece having screwed engagement therewith comprising a cylindrical chuck body, a thrust ring slidably and non-rotatably mounted on the chuck body, means on the said body on which the work-piece is fixed by screwed engagement against the thrust member, a plurality of cams each comprising a pin pivotally engaged in a radial hole in the chuck body and a head on the pin forming the cam face on one side against which the thrust ring bears and a lever on the other side, a cam control ring rotatably mounted on the chuck body and having slots therein for engaging the said cam levers, and spring means for holding the cam ring in position with the cams butting against the thrust ring and against the spring pressure of which the cam ring is rotated when the cams are moved away from the thrust member.

3. A chuck for holding a work-piece having screwed engagement therewith comprising a cylindrical chuck body, a thrust ring slidably and non-rotatably mounted on the body, a taper stem detachably fixed in a taper bore of the chuck body and having a screwed threaded head on which the work-piece is fixed by screwed engagement and against the thrust member, a plurality of cams pivotally mounted on the body of the chuck and forming movable abutment members against which the thrust member bears and which are adapted to be pivoted away from the thrust member, a cam control ring rotatably mounted on the chuck body and coupling the cams together so that they rotate in unison, spring means for holding the cam ring in position with the cams butting against the thrust ring and against the spring pressure of which the cam ring is rotated when the cams are moved away from the thrust member.

4. A chuck for holding a work-piece having screwed engagement therewith comprising a cylindrical chuck body, a thrust ring slidably and non-rotatably mounted on the chuck body, means on the said body on which the work-piece is fixed by screwed engagement therewith and against the thrust member, a plurality of cams each comprising a pin pivotally engaged in a radial hole in the chuck body and a head on the pin forming the cam face on one side against which the thrust ring bears and a lever on the other side, a cam control ring rotatably mounted on a chuck body and having slots therein for engaging the said cam levers, spring means for holding the cam ring in position with the cams butting against the thrust ring and against the spring pressure of which the cam ring is rotated when the cams are moved away from the thrust member, a trip lever mounted on one of the cams, and a stop on a stationary part of the machine against which the trip lever moves whilst the chuck is rotating to move the cams away from the thrust ring.

5. A chuck for holding a work-piece having screwed engagement therewith comprising a cylindrical chuck body, a thrust ring slidably and non-rotatably mounted on the body, a taper stem detachably fixed in the taper bore of the chuck body and having a screwed threaded head on which the work-piece is fixed by screwed engagement therewith and against the thrust member, a plurality of cams pivotally mounted on the body of the chuck and forming movable abutment members against which the thrust member bears and which are adapted to be pivoted away from

the thrust member, a cam control ring rotatably mounted on the chuck body and coupling the cams together so that they rotate in unison, spring means for holding the cam ring in position with the cams butting against the thrust ring and against the spring pressure of which the cam ring is rotated when the cams are moved away from the thrust member, a trip lever mounted on one of the cams, a spring controlled pawl mounted on a stationary frame against which the trip lever moves whilst the chuck is rotating to move the cams away from the thrust member and means for holding the pawl out of the path of the trip lever.

6. A chuck for holding a work-piece having screwed engagement therewith comprising a cylindrical chuck body, a thrust ring slidably and non-rotatably mounted on the chuck body, means on the said body on which the work-piece is fixed by screwed engagement therewith and against the thrust member, a plurality of cams each comprising a pin pivotally engaged in a radial hole

in the chuck body and a head on the pin forming the cam face on one side against which the thrust ring bears and a lever on the other side, a cam control ring rotatably mounted on the chuck body and having slots therein for engaging the said cam lever, spring means for holding the cam ring in position with the cams butting against the thrust ring and against the spring pressure of which the cam ring is rotated when the cams are moved away from the thrust member, a double armed lever on the outer end of one cam, a pair of spring pressed pawls mounted on a fixed frame with the pawls arranged so that one pawl will contact with one arm to turn the lever when the chuck is rotating clockwise whilst the other pawl will contact with the other arm and turn the lever when the chuck is rotating anti-clockwise, a lever on the pivot pin of each pawl and a slide mounted on the said frame in respect of each lever for co-acting with the respective slide for holding the pawl in an inoperative position.

GEORGE THORNHILL.
